(57) **CLAIM**

The ornamental design for a syringe as shown and described.

DESCRIPTION

FIG. 1 is a top front perspective view of a syringe, comprised of a grip and a plunger, according to the claimed design;

FIG. 2 is a bottom front perspective view of FIG. 1;

FIG. 3 is a left rear perspective view of FIG. 1;

FIG. 4 is right rear perspective view of FIG. 1;

FIG. 5 is a front view of FIG. 1;

FIG. 6 is a rear view of FIG. 1;

FIG. 7 is a top perspective view of the plunger of FIG. 1;

FIG. 8 is a bottom perspective view of FIG. 7;

FIG. 9 is a front view of FIG. 7;

FIG. 10 is a left side view of FIG. 7;

FIG. 11 is a top view of FIG. 7; and,

FIG. 12 is a bottom view of FIG. 7.

The broken lines of equal length dashes in the drawings illustrate portions of the syringe and form no part of the claimed design. The break lines having a jagged element indicate that the appearance of any portion of the syringe immediately outside of the break lines forms no part of the claimed design.
